D. magnuson.

UNITED STATES PATENT OFFICE.

HARRY A. THORDOX, OF CHICAGO, ILLINOIS.

CURTAIN FIXTURE.

Application filed March 29, 1922, Serial No. 547,686. Renewed January 31, 1924.

To all whom it may concern:

Be it known that I, HARRY A. THORDOX, a citizen of the United States, residing at Chicago, in the county of Cook and State 5 of Illinois, have invented certain new and useful Improvements in Curtain Fixtures, of which the following is a specification.

My invention relates to curtain fixtures and has for one of its objects the provision 10 of a simple and efficient device for holding curtains, draperies and the like for windows.

A further object is the provision of a simple and efficient curtain support which can 15 be easily and quickly applied to a window casing and curtain.

A still further object is the provision of a simple and efficient holder in the form of a stamping having means for quickly and 20 easily attaching it to a window casing and a means for quickly and easily attaching it to a curtain.

Other objects will appear hereinafter.

An embodiment of my invention is illus- 25 trated in the accompanying drawing forming a part of this specification, in which—

Fig. 1 is a fragmental view of a window casing and curtain with a curtain support embodying my invention;

Fig. 2 is a similar view showing my im- 30 proved support applied in a different position; and

Fig. 3 is an enlarged view in perspective 35 of one of my improved curtain supports with a curtain supporting member attached thereto.

Referring more particularly to the drawing, I have indicated a fragment of a window casing 4 and a fragment of a curtain 5 stretched across the sides of the window casing. The curtain 5 is intended to represent any desirable sort of curtain, whether a sash curtain which is attached to only a part of the casing, or any other kind of curtain. 40 Such curtains usually have a loop at their tops through which a flexible member 6 is passed to support them. The ends of the member 6 are usually attached to the frame 4 in some manner.

My improved device consists of a stamping 7, or other body, having a plurality of prongs 8 by means of which it is attached to the frame 4. In the form of my invention shown I have indicated the plate 7 as 45 being substantially rectangular with a

sharpened projection 8 at each corner. From the front side of the plate 7 is struck up a member 9 which is bent into the form of a hook and is adapted to receive the flexible member 6 on which the curtain hangs. 60 In the present embodiment I have indicated the member 6 as being a coiled spring, but it will be understood that this may be of any desired form of curtain support.

Where the member 7 is not a stamping 65 the member 9 can be any form of projection for holding the flexible member 6.

In Fig. 1 I have indicated the plate 7 as being on the front sides of the casing parts 4 and in these positions the member 6 ex- 70 tends away from the hook 9 in the position indicated in Figs. 1 and 3. Sometimes it is desirable to set the curtain in between the frame parts 4, and in such a case the plates 7 are placed against adjacent sides of the 75 casing parts 4, as clearly indicated in Fig. 2. Here the flexible member 6 pulls directly outwardly on the hook 9.

Each member 6 will require two of my improvements, one at each end thereof, as 80 clearly indicated in Figs. 1 and 2. It is sometimes desirable to support a curtain 5 at the top and bottom, or in any other manner, and it will be apparent that more than one flexible member 6 and supports at the 85 ends thereof may be supplied when desired.

I have illustrated the preferred form of my invention, but it will be apparent that variations and changes may be made in the details of the device without departing from 90 the spirit of my invention set forth in the appended claim.

I claim:

A curtain fixture comprising a flat rectangular plate, an integral window casing 95 engaging point at each corner of said rectangular plate disposed at a right angle to the latter, and an integral hook cut out and struck up from the central portion of said plate with a portion of said hook disposed substantially perpendicular to the plate on the opposite side of the latter from said points and another portion of said hook disposed in a curve facing the cut out portion 100 of said plate.

In testimony whereof I have signed my name to this specification on this 24th day of March, A. D. 1922.

HARRY A. THORDOX.
